(57) **CLAIM**

The ornamental design for a hearing aid tool as shown and described.

DESCRIPTION

FIG. 1 is a perspective view of the bottom left side of a hearing aid tool showing my new design.

FIG. 2 is a perspective view the top right-side of the hearing aid tool of FIG. 1.

FIG. 3 is an enlarged detail view of the bottom left side of the hearing aid tool of FIG. 1.

FIG. 4 is an enlarged detail view of the top right-side of the hearing aid tool of FIG. 2.

FIG. 5 is a bottom plan view of the hearing aid tool of FIG. 1.

FIG. 6 is a left side elevational view of the hearing aid tool of FIG. 1, the right side being a mirror image thereof.

FIG. 7 is a top plan view of the hearing aid tool of FIG. 1; and,

FIG. 8 is a front elevational view of the hearing aid tool of FIG. 1.

(Continued)

The dashed lines in the figures depict portions of the hearing aid tool that form no part of the claimed design.
